UNITED STATES PATENT OFFICE

JOHN J. N. VAN HAMERSVELD, OF CLEVELAND HEIGHTS, OHIO, ASSIGNOR TO THE ROTOR AIR TOOL COMPANY, OF CLEVELAND, OHIO, A CORPORATION OF OHIO

ROTARY MOTOR TOOL

Application filed October 12, 1927. Serial No. 225,682.

This invention relates to a fluid pressure motor, such, for example, as a pneumatic motor employed for operating a suitable tool, such as a surfacing tool, although the invention is not limited to the particular tool which the motor rotates.

The principal object of the invention is to provide a construction which embodies to a high degree the features of compactness, efficiency, lightness in weight, and ease of assembly.

A further object is to provide a construction involving a cylinder body with a lateral extension for sliding blades, air ports and the like, together with end plates, the whole being so constructed that the plates can be fitted to the body and centralized thereon without the necessity for interfitting portions which would interfere with the space desired for fluid pressure passageways and which enables the inner sides of the plates where they engage the extension of the cylinder body to form smooth and uninterrupted guide surfaces for the abutment blades which reciprocate in the extension and whose inner edges engage the rotor, which surfaces are continuations of the surfaces of the plates which form the end walls of the cylinder.

30 A further object is to provide a construction wherein the cylinder body has a laterally projecting handle which supplies the air to the cylinder body, the motor having a governor mounted on the end of the motor 35 spindle for governing the speed of the motor, with suitable provision arranged without substantially increasing the bulk of the motor for conducting the air from the lateral extension of the cylinder body to which the 40 handle is attached to the governor chamber and back again to the extension before entering the main inlet passageway formed in the cylinder body.

The above and other objects are obtained 45 by my invention which may be here briefly summarized as consisting in certain novel details of construction and combinations and arrangements of parts which will be described in the specification and set forth in 50 the appended claims.

In the accompanying sheets of drawings wherein I have illustrated the preferred form of the invention, Fig. 1 is a plan view of a fluid pressure tool embodying the invention; Fig. 2 is a sectional view substantially along the line 2—2 of Fig. 1; Fig. 3 is a side view of one of the rotors of the tool; Fig. 4 is a sectional view of the same; Figs. 5, 6 and 7 are detached views showing, respectively, one of the end plates, the cylinder body, and the other end plates; Fig. 8 is an end view of the motor with the adjacent end plate removed; Fig. 9 is an inside view of one of the end plates showing the segmental flange for centralizing the end plate on the cylinder body; and Fig. 10 is a side elevation of the cylinder body of Fig. 8 looking toward the cylinder extension.

Referring now to the drawings, the tool herein illustrated includes a motor having a cylinder body 15 formed in one piece, as hereinafter described, and closed at its ends by two end plates 16 and 17 having bearings 18 for a motor spindle 19 which is provided at one end with a suitable tool here shown as a surfacing disk 20, the outer flat face of which is adapted to be pressed against the work to be surfaced. Other tools may be employed in place thereof.

The cylinder body has a cylindrical bore 80 extending from end to end therethrough, and mounted midway of the ends of the cylinder body is an annular dividing partition 21 held in place by radially disposed screws 22 passing through the cylinder body into the periphery of the partition. On opposite sides of the partition and keyed or otherwise secured to the shaft are two eccentric rotors 23, shown detached in Figs. 3 and 4, which rotors are spaced 180° apart and, as illustrated in Figs. 2, 3 and 4, are hollowed out for the sake of lightness with the metal disposed so that each is in static and kinetic balance. The cylinder body is formed on the side with a lateral extension 24 and formed in this extension and extending inward from opposite ends of the cylinder body toward but not entirely to the center, and also formed from the opposite end of the extension to the inner cylindrical bore, are two guide slots 95 100

25 which receive sliding abutments 26 whose inner ends are maintained in contact with the two rotors 23. The thickness of the wall between these guide slots 25 is the same as the thickness of the partition 21, as shown in Fig. 2. Additionally, the extension 24 has formed from side to side therethrough on opposite sides of the guideways 25 a main inlet passageway 27 for the motive fluid 10 which is generally air and will be so referred to hereafter, and a main air outlet passageway 28. There is formed also in the extension and extending from the outer face thereof to the inner bore a series of auxiliary inlet 15 passageways 29 which intersect the main inlet passageway 27, extending at right angles thereto, and a series of auxiliary exhaust passageways 30 which intersect the main exhaust passageway 28. From the outer ends 20 of the auxiliary inlet passageways 29 ports 31 extend to the outer portions of the guideways 25 so that air pressure is exerted on the ends of the abutment blades which will, therefore, be held yieldingly against the two 25 eccentric rotors 23.

It will be observed particularly by reference to Figs. 5, 7 and 9 that the end plates have a contour substantially the same as the contour of the cylinder body viewed from the 30 end. That is to say, each has a substantially circular portion closing the end of the cylinder body and each has an extension lying alongside the lateral extension 24 of the cylinder body. Likewise, it will be observed that 35 each of these end plates has a segmental, inwardly extending flange 32 which is circular except for an arc-shaped portion omitted at and adjacent the extension of the end plate, note particularly Fig. 9. These end plates fit 40 flat against the substantially annular portions at the ends of the cylinder body and the extensions of the end plates fit flat against the ends of the cylinder body extension, and the substantially circular flanges 32 fit closely 45 over the outer wall of the cylinder body so as to centralize the end plates so that the bearing receiving portions are truly concentric with the axis of the machine. It is to be noted also that the inner faces of the end plates are, 50 with this construction, flat, the substantially annular portions forming bearing surfaces for the rotors and the extensions forming guides for the abutment blades, the guide 55 surfaces for the abutment blades and the bearing surfaces for the rotors being continuous and uninterrupted. The adjacent engaging faces of the cylinder body and end plates are carefully machined and the end plates are not 60 only centralized but the parts are closely fitted together to avoid leakage without the necessity for gaskets and there is avoided the necessity for dowels, bushings and the like heretofore required in tools of this kind to 65 align the parts, especially in the best designed

tools where accuracy, efficiency, and lightness are required.

The machine has two handles, one, designated 33, being secured to a lug 34 formed on the side of the cylinder body, and the other, designated 35, being secured onto the end of the cylinder extension 24. The handle 35 has a passageway 36 extending therethrough for the air which operates the motor, the air being supplied to this passageway through an inlet 70 opening 37 formed at the extreme end of the handle and adapted to receive a suitable supply tube or hose. Also extending longitudinally of the handle parallel to the inlet passageway 36 is a lubricant passageway 38 from 75 which lubricant may pass to the air passageway 36 at a rate dependent upon the position of an adjustable needle valve 39.

The handle 35 carries also a valve lever 40 which can be operated conveniently by the 80 thumb or finger of the operator's hand engaging the handle 35. This lever is mounted on a stem having at its inner end an eccentric 41 which, by means of a pin 42, is adapted to transmit movement to a sliding valve 43 engaged by a spring 44, and by this sliding movement adapted to cover and uncover ports formed in the valve sleeve 45, which ports are adapted to place the passageway 36 85 in communication with a passageway 46 90 formed in the base of the handle 35. It might be here stated that a portion of the base of the handle forms a covering for the cylinder extension 24, closing the outer ends of the guideways 25 and closing the auxiliary inlet 95 and exhaust passageways 29 and 30 as well as the ports 31. The passageway 46 extends laterally from a point adjacent the valve 43 to the end face of the handle.

Ordinarily, the air would pass substantially directly from the handle to the main inlet passageway 27 of the cylinder, but not so in this instance for the reason that I extend the motor spindle 19 through and beyond the end plate 16 and mount on the extension a speed controlling governor 47 which in construction may be similar to that disclosed in my prior application Serial No. 122,351, filed July 14, 1926, Patent No. 1,674,579, granted June 19, 1928. This governor is housed in a chamber 48 formed in a cap 48 which is secured to the outer face of the end plate 16. 105

In order that the air may be conducted from the passageway 46 to the governor, I form in the end plate 16 directly opposite the adjacent abutment blade 26 a passageway 49 whose outer portion is radially disposed and terminates in the end of the extension of this end plate in line with the inner end of the passageway 46 formed in the handle 35. It 110 will be noted that the base of the handle fits against and in contour corresponds to the shape or contour of the end of the cylinder body extension and of the end of the extension 115 of the end plate 16. The outer end of 120 125 130

passageway 49 is in registration with the inner end of passageway 46 and it extends radially inward and then outward to the outer face of the end plate 16, and here the inner 5 end of the passageway 49 is in registration with a passageway 50 extending through the cap 48 to a point opposite the center line of the motor where a hollow extension of the governor extends into the passageway, as 10 illustrated in Fig. 2.

The air may enter from the passageway 50 into the governor, and when the motor is in operation it passes out through the weight controlled ports of the governor into the 15 chamber 48^a. From this chamber the air passes through a passageway 51 formed partly in the cap and partly in the end plate 16, as indicated by dotted lines in Figs. 1 and 2, to the main air inlet passageway 27 formed 20 in the cylinder body extension. From this last mentioned passageway the air may pass to both of the cylinder chambers in the well known manner. The air is exhausted by way of the main exhaust passageway 28 which has 25 small exhaust openings 28^a extending laterally therefrom to the outer side of the cylinder body extension.

From the above it will be seen that the operator, by manipulating the valve lever 40, 30 allows the air to pass from the handle to the passageways formed in the base of the handle adjacent the outer end of the cylinder extension and in the end plate 16 and through the cap secured to the outer face thereof 35 into the governor which is mounted on and rotated by the motor spindle, then to the governor chamber and back again to the cylinder body extension. In the passage of air in this more or less circuitous manner through the 40 various parts of the machine from the handle on the cylinder extension to the governor on the motor spindle and back again, there is no leakage of air, the passageways being formed largely by coring the parts through which 45 they extend and without in any material respect increasing the bulk of the machine, the features of compactness and rigidity as well as lightness being maintained throughout the design. The manner in which the 50 end plates are centralized on the cylinder body is a factor in the attainment of compactness, and as these end plates are accurately centered close clearances can be provided between the stationary and rotating parts, resulting 55 in reduced size and increased power.

It will be seen, therefore, that by the construction described above I have attained to a high degree the results and advantages 60 enumerated in the early part of the specification, and while I prefer the construction herein illustrated, changes may be made without departing from the spirit and scope of the invention.

Having thus described my invention, what 65 I claim is:

1. In a fluid pressure tool, a motor having a stationary portion provided with a lateral extension and having a cylinder bore, a spindle having a rotor in the cylinder bore, a handle secured to said extension and having a fluid passageway extending therethrough, a governor at one end of the spindle and passageways for conducting fluid from the handle to the governor and from the governor back to the said lateral extension. 75

2. In a fluid pressure tool, a motor having a cylinder body with a cylinder bore and with a lateral extension, a spindle having a rotor in the cylinder bore, a governor at one end of the spindle, end members at the ends of the cylinder body and one having a governor chamber, a handle secured to the end of the cylinder body extension and having a fluid passageway, an inlet passageway formed in the cylinder body extension, and passageways extending from the handle to the governor chamber and back from the governor chamber to said main inlet passageway of the cylinder body extension. 85

3. In a fluid pressure tool, a motor comprising a cylinder body with a cylinder bore and with a lateral extension, a spindle having a rotor in said bore, end members closing the ends of the cylinder body, a handle having a fluid passageway and a controlling valve, a main inlet passageway formed in the cylinder body extension, a governor connected with the spindle, a governor chamber formed in one of the end members, and passageways extending from the valve to the governor and back to said main inlet passageway. 90

4. In a fluid pressure tool, a motor comprising a cylinder body with a cylinder bore and with a lateral extension, a spindle having a rotor in said bore, end members closing the ends of the cylinder body, a handle having a fluid passageway and a controlling valve, a main inlet passageway formed in the cylinder body extension, a governor connected with the spindle, a governor chamber formed in one of the end members, and passageways extending from the valve to the governor and back to said main inlet passageway, all said passageways except the main inlet passageway being formed independently of the cylinder body. 105

5. In a fluid pressure tool such as described, a motor comprising a cylinder body having a cylinder bore and having a lateral extension, a spindle having a rotor in said bore, said cylinder body extension having abutment blades slidable therein and at their inner ends adapted to engage the rotor, and said cylinder body extension having a main inlet passageway communicating with the cylinder bore, a governor connected with the spindle, end members at the ends of the cylinder body, one of the end members having a chamber formed therein receiving the governor, a handle secured to the said extension and hav- 115 120 125 130

ing a valve controlled fluid passageway formed therein, and passageways extending from the valve to the governor and from the governor chamber back to said main inlet passageway.

- 5 6. A fluid pressure motor comprising a cylinder body having a cylinder bore and provided with a lateral extension, a spindle having a rotor in said bore, end plates secured to the ends of the cylinder body, a cap secured to one of said end plates, a governor connected with the spindle and housed within said cap, a handle secured to the end of said cylinder body extension and having a valve controlled fluid passageway extending therethrough; abutment blades and a main inlet passageway in said cylinder body extension, and passageways extending from the valve to the governor and from the governor chamber back to said main inlet passageway of the cylinder body extension.
- 10 15 20

In testimony whereof, I hereunto affix my signature.

JOHN J. N. VAN HAMERSVELD.
